SKI SLEIGH

Harold C. F. Lammers and Bessie B. Lammers,
Akron, Ohio

Application October 5, 1951, Serial No. 249,976

1 Claim. (Cl. 280—21)

1

This invention relates to sleds or sleighs, and more particularly, has reference to a structure falling within this category, wherein a pair of ski-like runners are attached to the body of the device, and are tilttable transversely through the provision of a novel steering means, thus to bank said runners and cause the entire structure to be turned in either direction, with a high degree of facility.

It is one important object of the present invention to provide a structure of the character described wherein the weight of the structure will be evenly distributed so as to increase measurably the facility with which the entire structure may be steered.

Another important object is to provide, in a ski sleigh or sled, a steering control system wherein radius rods or the like will be eliminated completely, and all lever movement will be horizontal and of highly simplified design, thus to provide a structure wherein the several parts will be of simple construction, and will not readily get out of order.

Another important object is to provide a ski sleigh of the character stated, which will permit the use of conventional skis as runners therefor, and which will make use of the cambered construction of standard skis to make easier the steering of the sleigh.

Briefly, the structure comprises a sled body having a pair of ski-like runners extending along opposite sides thereof, said runners being hingedly connected to the body so as to be tilttable transversely. Incorporated in the structure is a steering bar, having a crank arm rigid therewith that is joined to a medially fulcrumed lever, so that the lever is rocked upon the sled body upon movement of the steering bar. The lever, in turn, is connected to a transversely extending control bar, joined at opposite ends to upstanding arms rigid with the respective runners, thus to cause the runners to be jointly tilted or banked in a direction transversely of the sled body, upon reciprocable movement of the control bar transversely of said body.

Other objects will appear from the following description, the claims appended thereto, and from the annexed drawings, in which like reference characters designate like parts throughout the several views, and wherein:

Figure 1 is a top plan view of a ski sleigh formed in accordance with the present invention;

Figure 2 is a side elevational view;

Figure 3 is a bottom plan view;

2

Figure 4 is a view similar to Figure 3 in which the runners have been tilted transversely for the purpose of steering the sleigh;

Figure 5 is a transverse sectional view, taken on line 5—5 of Figure 2;

Figure 6 is a transverse sectional view taken on line 6—6 of Figure 2;

Figure 7 is a longitudinal sectional view on line 7—7 of Figure 1;

10 Figure 8 is a transverse sectional view taken on line 8—8 of Figure 7;

Figure 9 is a fragmentary side elevational view of the hinge connection between one of the runners and the sled body; and

15 Figure 10 is a perspective view of the steering control mechanism, the steering bar being shown in dotted lines.

Referring to the drawings in detail, the sled body includes a longitudinally and centrally disposed center piece 11 of flat, elongated formation, said center piece being formed preferably from a suitable length of flat wood stock.

Extending longitudinally of the center piece 11, at opposite sides thereof, are side pieces 12, 25 that cooperate with the center piece 11 to form a flat body portion adapted to support one or more persons.

Adjacent the rear end of said body portion, the center and side pieces 11, 12 are joined by a rear cross member 14, that underlies said center and side pieces, and is rigidly secured thereto in any suitable manner.

A front cross member 16 underlies the center and side pieces adjacent the front ends of the structure, and is also secured to said pieces, thus to rigidly connect the component parts of the body portion forwardly and rearwardly thereof.

The respective cross members 14, 16 project beyond the opposite sides of the body portion and are rigidly connected to hand holds 18 that extend longitudinally of opposite sides of the body portion, and are supported upon the projecting ends of the cross members.

45 Fixedly connected to the undersides of the projecting ends of the front and rear cross members are depending supports of inverted V-shape, said supports being designated 20 (see Figure 9) and being integrally formed at their lower ends with oppositely extended horizontal extensions 22 secured fixedly to opposite ends of horizontally disposed hinge plates 24. Hinge plates 26 cooperate with the hinge plates 24 to provide piano hinges, said hinge plates swinging upon axes disposed longitudinally of opposite

50 sides of the sled structure.

3

Rigid with the lower edges of the hinge plates 26 are plate members 28 rigidly secured to the top surfaces of runners 30.

The runners 30 can be, and preferably are, a conventional pair of skis properly cambered for efficient distribution of weight.

It will be seen that the center pieces 11, 12, the cross members 14, 16, and the depending supports 20 with their associated hinge plates 24, cooperate to define a body on which the runners 30 are hingedly mounted for swinging movement about axes disposed longitudinally of the runners and spaced above said runners.

A steering bar 32 is disposed transversely of the body of the ski sleigh, adjacent the front end of the body, and has its opposite ends projecting beyond the opposite sides of the body, so as to be adapted to be steered either by the hands or feet of one riding upon the device. The steering bar 32 is rigidly connected, intermediate opposite ends thereof, to a depending pin 34, which is rotatably journaled in the front end portion of the center piece 11, thus to rockably mount the steering bar 32 upon the body of the structure for swinging movement in a horizontal plane.

Rigid with the pin 34, and underlying the body portion of the sled defined by the members 11, 12, is a crank arm 36, extending radially from the pin 34 and adapted to be swung upon rotation of the pin, which rotation is of course caused by movement of the opposite ends of the steering bar 32 longitudinally of the sled body.

The crank arm 36 extends rearwardly from the pin 34, and at its rear end is formed with a longitudinal slot 38, through which a connecting pin 40 extends, the connecting pin 40 serving to provide a pivotal connection between the crank 36 and the front end of a lever 42, that is disposed longitudinally of the sled body.

The lever 42 is fulcrumed intermediate opposite ends thereof upon a pivot pin 44 that extends through the center piece 11 and front cross member 16 to connect the same, the lever 42 swinging in a horizontal plane.

At its rear end, the lever 42 is pivotally connected to the forwardly extended portion of an angle bracket 46, which is provided with a depending leg rigidly secured in any suitable manner to the intermediate portion of a reciprocable cross bar 48. The cross bar 48 is mounted to be reciprocated transversely of and below the body portion of the structure, and will be given movement upon rocking of the lever 42 on its pivot 44.

At its opposite ends, the cross bar 48 has pivotal connections 50 to the upper ends of a pair of arms 52 which may be of inverted V-shape, and which are rigidly secured at their lower ends to plates 54, that are secured to the top surfaces of the respective runners 30.

In use, if the ski sleigh is to be directed upon a straight course, the steering bar 32 is disposed perpendicularly to the longitudinal center line of the structure, as shown in Figure 1 or 3. In this position of the steering bar, the flat, wide runners 30 are disposed in a common plane parallel to the plane of the body portion of the device, and are in full contact, along their bottom surfaces, with the supporting surface S.

If, however, the sled or sleigh is to be steered to right or left, it is merely necessary to rock the steering bar 32 to a position such as that shown, for example, in Figure 4. This swings the crank arm 36, which in turn rocks the lever 42 upon its pivot 44, causing the cross bar 48 to be shifted transversely of the device in one direction.

4

Upon movement of the cross bar 48 in this manner, the arms 52 will be inclined out of verticality, to the position illustrated in Figure 8. Since said arms are rigid with the runners 30, the runners will in turn be tilted transversely to the position shown in Figure 8, the runners swinging on the piano hinges defined by the hinge plates 24, 26.

The rider, as will be appreciated, may either lie down upon the body portion of the device or sit up, and can steer either by pulling the steering bar 32 by hand, or by pulling a rope, not shown, connected to the opposite ends of the steering bar. The steering bar, in this connection, is formed with end openings through which such a rope may be inserted.

When the rider rocks the steering bar 32 for the purpose of turning the sled to right or left, he exerts his body weight to that side of the structure toward which he desires to turn the sled. This shifting of body weight, occurring simultaneously with the tilting of the ski runners, causes the sled to begin a curving movement in the desired direction. This curving movement obtains due to the fact that the upcurved front end portions of the runners cause more weight to be placed upon the inside runner. The inside ski or runner then becomes, in effect, the leading runner while the outside ski or runner becomes a trailing runner, causing the curving movement of the entire device. The operation of banking the ski runners transversely for the purpose of changing the direction of movement of the sleigh is not unlike that which occurs when a skier changes the direction of his movement.

We believe that the structure illustrated and described possesses certain characteristics which may be worthy of note at this point. For example, the entire structure can be manufactured at relatively low cost, considering the benefits to be obtained thereby, and in fact, can be readily formed by modifying an ordinary sled body to permit said body to receive a conventional pair of skis, the body being, of course, equipped with a steering mechanism such as that illustrated and described.

Further, it is considered to be important that the entire steering control mechanism is shiftable only in a horizontal plane, the component parts of said mechanism being of simplified construction, so as to reduce the total number of parts to a minimum and so as to provide a steering means which will be durable and will not readily get out of order.

It is believed clear that the invention is not necessarily confined to the specific construction illustrated and described, since such construction is only intended to be illustrative of the principles of operation and the means presently devised to carry out said principles, it being considered that the invention comprehends any minor changes in construction that may be permitted within the scope of the appended claim.

What is claimed is:

A sleigh comprising a body having a body portion adapted to support a rider; a plurality of supports carried by said body portion at opposite sides thereof, said supports being rigid at their upper ends with and depending from the respective sides of the body portion; runners hingedly connected to the lower ends of the respective supports, the axes on which said runners are hinged for swinging movement being arranged longitudinally and centrally of the runners and being spaced above the upper surfaces of the run-

ners; arms rigid with and upstanding from the respective runners; a bar of rigid formation from end to end thereof connected pivotally at its opposite ends to the upper ends of the respective arms and arranged transversely of the body so as to swing the arms to inclined positions when shifted transversely of the body in a selected direction, thus to tilt the runners bodily on their hinge connections so as to steer the sleigh in a direction selected by said rider, the pivotal connections of the bar to the respective arms being confined to relative movement of the arms and bar about axes paralleling the hinge axes of the runners, said bar including an angle bracket rigidly secured to and extended forwardly from the midlength point of the bar, said bracket having a slot; a lever fulcrumed between its ends upon the underside of said body for swinging movement in a horizontal plane, said lever having a pin at one end extending through the slot for pivotally connecting the lever at said end to the bar, the bar having rectilinear movement transversely of the body responsive to rocking of the lever on

its fulcrum; a steering bar extending transversely of and overlying the body and fulcrumed intermediate its ends upon the body; and a crank arm rigid with and extended rearwardly from said steering bar toward the first-named bar and having a slot, said lever having a pin extended through the second-named slot to pivotally join the crank arm to the other end of said lever, thus to rock the lever responsive to pivotal movement of the steering bar under the control of a rider.
